UNITED STATES PATENT OFFICE.

PETER JOHNSON, OF BOSTON, MASSACHUSETTS.

NICOTIN-EXTRACTOR AND SMOKE-COOLER FOR TOBACCO-PIPES.

SPECIFICATION forming part of Letters Patent No. 639,397; dated December 19, 1899.

Application filed March 17, 1899. Serial No. 709,388. (No model.)

To all whom it may concern:

Be it known that I, PETER JOHNSON, of Boston, (Jamaica Plain,) in the county of Suffolk and State of Massachusetts, have invented 5 certain new and useful Improvements in Nicotin-Extractors and Smoke-Coolers for Tobacco-Pipes, of which the following is a description sufficiently full, clear, and exact to enable those skilled in the art to which it applies 10 pertains or with which it is most nearly connected to make and use the same.

This invention has relation to tobacco-pipes of the kind for which Letters Patent of the United States were granted to me September 15 13, 1898, No. 610,757.

While the means shown and described in said patent are well adapted for use in long-stem pipes, they are not applicable with the same full beneficial results to short-stem 20 pipes. Hence I have devised my present invention with the object of providing short-stem pipes with means which will serve to appreciably cool the smoke in its passage from the burning tobacco in the bowl to the smoker's mouth and at the same time extract or 25 trap the nicotin and other unconsumed poisonous substances from the smoke.

To these ends my invention consists, broadly, of a smoke-cooler and nicotin-extractor for tobacco-pipes comprising a rod or wire having a helical groove formed in its surface and extending from end to end, the said rod being provided with a collar or ring at a suitable point intermediate of its ends.

Reference is to be had to the annexed drawings, and to the letters marked thereon, forming a part of this specification, the same letters designating the same parts or features, as the case may be, wherever they occur.

Of the drawings, Figure 1 is a longitudinal sectional view of a crooked short-stem tobacco-pipe embodying my invention, the cleaning-coil being omitted. Fig. 2 shows a straight short-stem pipe equipped with my invention, the stem and mouthpiece being represented in section and the cleaning-coil being shown as applied to the nicotin-extracting part of the device. Fig. 3 is a detached view of the nicotin-extractor and smoke-cooler. Fig. 4 is a perspective view of the ring or collar forming a part of the means shown in Fig. 3. Fig. 5 is a side and end

view of a nicotin-cleaning device designed to be used in connection with the nicotin-extractor.

In the drawings, *a* designates the bowl of a short-stem pipe. *b* is the stem, and *c* is the mouthpiece. In Fig. 1 the stem and mouthpiece are shown as crooked or curved, while in Fig. 3 these parts are represented as straight.

In carrying out my invention I provide a rod *d*, forming a helical groove *e* in the surface therearound, which groove extends from end to end of the rod. As herein shown, the 65 rod *d* is made by taking a length of straight wire *f*, preferably of aluminium, and wrapping or coiling another wire *g* in a helical manner therearound, so that a substantial helical groove *e* is formed between the coils. 70

h designates a collar or ring adapted to fit on the helically-grooved rod *d* and to be soldered or otherwise affixed thereon, leaving the groove *e* open through the collar. If the collar is soldered on the rod, a removable core, 75 as a string, may first be laid into the groove, so that it may be protected against being filled by solder. After soldering is effected the core may be removed.

In boring out the smoke-hole *i* or conduit 80 in the stem and mouthpiece of the pipe I make it just sufficiently large to admit the helically-grooved rod *d* therein, the fit being snug enough to make sure of the passage of the smoke drawn from the burning tobacco 85 in the bowl through the helical groove and not between the sides of the rod and the conduit. The smoke-hole *i* in the stem *b* is enlarged at the point where the collar *h* comes when the rod is in position, so as to form a 90 chamber *j* *j'* on opposite sides of the collar, in which chambers smoke drawn into the stem of the pipe may collect outside of the helical groove in the rod *d*.

I have found from experience that with a 95 tobacco-pipe equipped with my invention the smoke in its passage from the bowl to the mouthpiece, by reason of its lengthy course through the helical groove of the rod *d*, will be materially cooled and that a full draft may 100 be contained in the stem and mouthpiece, so that one draft may be cooling in the stem while the one just drawn is being enjoyed and disposed of.

An important result gained in the use of my improvement is that the nicotin and other unconsumed substances in the tobacco-smoke are trapped in that portion extending 5 below the collar *h* and no appreciable quantity escapes above the same.

Experience has shown that after considerable use of my improved device in a pipe the rod *d* below the collar *h* will become thickly 10 coated with nicotin and gummy substances, while the portion above the collar will be substantially free from such substances. I may provide a short coil of wire *l*, with a collar *m* on one end thereof, which coil may be turned 15 on the rod *d* below the collar *h* and by turning the same up and down thereon and through the collar *h* free the device from the nicotin-gum.

Instead of having the smoke pass through 20 the collar *h* it may pass around the same through kerfs or slots *n*, cut in the periphery of the collar.

As shown, the invention can be applied to pipes having any practical form of stem, and 25 while it has been described and illustrated as applied to short-stem pipes it is obvious that it is capable of use in long-stem pipes as well.

I propose, as has already been indicated, to 30 make the rod *d* and its equipments of aluminum or other suitable material and to make the said device a thing capable of separate manufacture and sale.

Though I have described a particular way 35 or method of manufacturing the rod *d*, I do not confine my invention to any particular way of making it. It is sufficient for the purposes of my invention that the rod should be grooved to lengthen the traverse of the smoke through the stem of the pipe and be provided 40 with a collar *h* or a device that will accomplish the same function.

Having thus explained the nature of the in-

vention and described a way of constructing and using the same, though without attempting to set forth all of the forms in which it may 45 be made or all the modes of its use, it is declared that what is claimed is—

1. A nicotin-extractor consisting of a rod adapted to be inserted in the smoke-conduit of a tobacco-pipe having a groove formed in 50 its outer surface of greater length than the length of the rod and extending from end to end thereof, and provided at a point intermediate of its ends with a collar *h* completely surrounding the rod, substantially as de- 55 scribed.

2. A nicotin-extractor for tobacco-pipes consisting of a rod provided on its exterior with a helical groove extending from end to end of the rod and at a point intermediate of 60 its ends with a collar *h* completely surrounding the rod, substantially as described.

3. The combination, with a tobacco-pipe having the smoke-conduit in its stem enlarged to form a chamber *j, j'*, of a nicotin-extractor 65 inserted in the smoke-conduit, said nicotin-extractor consisting of a grooved rod provided with a collar, the collar extending into the said chamber and dividing it, as set forth.

4. A nicotin-extractor for tobacco-pipes 70 consisting of a rod provided on its exterior with a helical groove, and at a point intermediate of its ends with a collar *h* completely surrounding it and having a short cleaning-coil *l* turned thereon, as set forth.

In testimony whereof I have signed my name to this specification, in the presence of two subscribing witnesses, this 18th day of February, A. D. 1899.

PETER JOHNSON.
